Primary Examiner — Selina Sikder(74) *Attorney, Agent, or Firm* — Foley Hoag LLP; Walter M. Egbert, III; Stephen Kenny(57) **CLAIM**

The ornamental design for a control switch for an electronic device, as shown and described.

DESCRIPTION

FIG. 1 is a perspective view of the control switch for an electronic device showing my new design;

FIG. 2 is a top view thereof;

FIG. 3 is a bottom view thereof;

FIG. 4 is a first side view thereof;

FIG. 5 second side view thereof;

FIG. 6 is a first end view thereof; and,

FIG. 7 is a second end view thereof.

Broken lines are used in the drawings to illustrate features that form no part of the claimed design.
